United States Patent Office

Des. 217,950
Patented July 7, 1970

217,950

SHOE

Arthur W. Einstein, Jr., New York, N.Y., assignor to Lord, Geller, Federico & Partners, Inc., New York,
N.Y.

Filed Dec. 3, 1968, Ser. No. 14,772

Term of patent 14 years

Int. Cl. D2—04

U.S. Cl. D2—269

FIG. 1

FIG. 2

FIG. 1 is a side elevational view of a shoe, showing our new design, the side opposite being substantially similar thereto;

FIG. 2 is a front elevational view thereof; and

FIG. 3 is a bottom plan view.

The essential feature of my design resides in the shoe sole portion.

I claim:

The ornamental design for a shoe, substantially as shown and described.
